UNITED STATES PATENT OFFICE

CHARLES DUERR, OF BROOKLYN, NEW YORK, ASSIGNOR, BY MESNE ASSIGNMENTS, TO
S. BRUNER, INC., OF NEW YORK, N. Y., A CORPORATION OF NEW YORK

STRAP FOR WRIST WATCHES

Application filed October 27, 1928. Serial No. 315,366.

This invention relates to flexible bands as, for example, straps for wrist watches, bracelets, ornamental neck bands or other articles of jewelry.

5 Although the present invention may have a variety of useful applications it is shown and described herein as employed to hold a wrist watch in position.

10 Wrist watches have attained considerable popularity and many types of bands or straps have been devised, beginning with the leather strap and developing into numerous straps constructed of metal.

15 The metal strap has gained favor, being free from the disadvantage of stretching and becoming damp from absorbed perspiration.

20 In the making of a wrist watch strap it is necessary to have flexibility so that the strap will take the shape of the wrist to the comfort of the wearer. It is also important to provide a strap of a smooth symmetrical appearance so as to make a pleasing addition to the watch which it secures in place.

25 In copending application Serial No. 262,737, filed March 19, 1928 and assigned to the assignee of the present invention, a wrist watch strap is shown composed of a metallic mesh and the present invention has for its object to provide a wrist watch strap of the same 30 general character as that mentioned in the said application but of smooth appearance and simulating a plain metal band and at the same time possessing the desired flexibility.

35 A wrist watch strap constructed in accordance with my invention is made up of a plurality of tubular metallic sections secured by pairs of locking elements enclosed by the sections which cooperate therewith to hold the members in locked relation.

40 The invention will be more fully understood by reference to the accompanying drawings in which:

45 Fig. 1 is a plan view of a strap made in accordance with the present invention attached to a wrist watch;

Fig. 2 shows a portion of a strap with a partly broken away section to show the locking elements;

50 Fig. 3 shows a tubular section with the locking members about to be inserted;

Fig. 4 is an edge view of a strap having a connector or fastener and

Fig. 5 is a modification of the elements constituting the latch and latch piece.

An embodiment of the invention may comprise a strap 10 composed of a plurality of tubular sections 11 which in the present construction are of sheet metal and of rectangular transverse cross section. The sections 11 are disposed in close adjacent relation to constitute a strap or band and are held in such relation by pairs of locking members 12 and 13. These locking members 12 and 13 which may be termed a latch and latch-piece respectively, serve to hold the sections 11 in flexible relation. The latch 12 is provided with a hook portion 14 and the latch-piece 13 is provided with a hook portion 15.

These hooks are arranged to extend over the edges of and to embrace adjacent walls 16 and 17 of adjacent tubular sections and the locking members are so proportioned and arranged that when moved into place within a tubular section a lip 18 on the latch 12 will engage with a lip 19 on the latch-piece 13.

75 For the purpose of holding the locking members in locked relation their combined width is so proportioned that surface 20 of the latch-piece 13 will engage wall 16 of a tubular section while the latch 12 is held 80 against the wall 17. By reason of the construction and material of the members they are sufficiently elastic to permit a slight spring so that the lips 18 and 19 may be snapped into engagement and by reason of 85 the opposing walls of the tubular section, such relation is maintained. Each of the locking members may occupy only a portion of the space within its tubular section, the remaining space being provided for the entrance of the hook portions 14 and 15, thus 90 it will be evident that if the tubular sections are made just sufficiently wide to admit the locking members the opening at the ends thereof will be entirely filled and a smooth 95 symmetrical appearance will result.

When a plurality of tubular sections 11 have been secured by a plurality of pairs of locking members, a slight relative movement of each of the sections may be had with the 100

result that the strap so constructed is of a flexible nature and when used as a band for a wrist watch will take the contour of the wrist and serve as well as a leather strap. 5 without the disadvantages above mentioned.

As shown in the drawings, a strap composed of a plurality of tubular sections may be readily attached to a watch 21 since end sections 11' and 11'' may have tubular extensions 22 and 22'' to provide apertures to receive pins 23 and 24 as commonly provided for securing a metallic strap to a watch. The free ends 25 and 26 may also be provided with sections having similar tubular extensions 27 and 28. The extensions 27 may be attached to a latch plate 29 adapted to engage with a notched member 30. The latch plate is provided with flanges 31 and 32 having serrations on their inner surface to grip the notched member 30. This lock or connector is more clearly shown in the above mentioned copending application.

As shown in Fig. 5 the locking members may be modified and as illustrated, the same 25 may include parts 33 and 34 having hook portions 35 and 36 respectively to secure sections 11. The member 34 may be provided with a head 37 adapted to be engaged by spring jaws 38 and 39 on the member 33. 30 The action and function of the latch members 33 and 34 is the same as the members indicated by the numerals 12 and 13 and provide a latch for securing the sections 11 in flexible relation. When the members 33 and 34 are inserted into opposite ends of a section 11 they are moved toward each other until the jaws 38 and 39 snap over the head 37, thus securing them against removal since it will be evident that the jaws are held from 40 movement away from the head by the walls of the enclosing section 11.

From the above it will be evident that the present invention provides a simple and effective construction for a chain or strap 45 wherein the various parts may be quickly and easily assembled and at relatively low cost.

Although a preferred embodiment of the invention is shown and described herein, it is to be understood that modifications may 50 be made therein without departing from the spirit and scope of the invention as set forth in the appended claims.

What is claimed is:

1. Means for connecting adjacent tubular sections in adjustable relation comprising pairs of coupling members, each of said members being of substantially U-shape, the legs of the opposite members of said pair extending into adjacent tubular sections, a latch on 55 the leg of one member and a latch piece on the leg of an oppositely disposed member, said latch and latch piece being held in engagement by contact with the wall of the tubular section enclosing said legs.
2. A device of the class described comprising

ing tubular sections, connector members of substantially U-shape having a long leg and a relatively short leg, said members being disposed in opposite ends of adjacent tubular members, with the long legs of opposite members extending toward each other and the short legs of opposite members disposed in adjacent tubular sections and means for engaging the ends of said oppositely disposed long legs to prevent an endwise movement of 70 said members from said sections. 75

3. A device of the class described comprising tubular sections, connector members of substantially U-shape having a long leg and a relatively short leg, said members being disposed in opposite ends of adjacent tubular members, with the long legs of opposite members extending toward each other and the short legs of opposite members disposed in adjacent tubular sections and means for engaging the ends of said oppositely disposed long legs to prevent an endwise movement of 80 said members from said sections, said oppositely disposed long legs being so proportioned as to engage the walls of a tubular section for retention in engaged relation. 85

4. A device of the class described comprising coupling members formed from sheet material and having two substantially parallel portions connected by a transverse portion, 90 said members being formed in pairs, one parallel portion of one member having a lip, one parallel portion of the other member having a lip said portions extending into opposite ends of a tubular section and disposed with 95 opposite lips in interlocking engagement, said portions having a combined width substantially equal to distance between opposite interior walls of the section whereby said lips are held engaged. 100

5. Means for attaching tubular sections in flexible relation comprising pairs of U-shaped members, a leg portion of one member having a latch and a leg portion of the other member having a latch-piece to provide inter-locking portions, said inter-locking portions being disposed within a tubular section, the remaining leg of each of said members being disposed in an adjacent tubular section to connect the same to the section enclosing the 115 inter-locking portions.

6. A device of the class described comprising a plurality of flat tubular sections, pairs of U-shaped members formed from sheet material, said members being so disposed that corresponding legs of each pair extend into opposite ends of adjacent tubular sections to connect the latter, one pair of said corresponding legs having engaging lips said legs being of a combined width substantially equal to the distance between opposite walls of their enclosing section whereby said lips are held in engagement. 120

7. A device of the class described comprising a plurality of flat tubular sections having 125

5 a given internal width and thickness, pairs of flat U-shaped members, the legs of said members being of a width equally to substantially one half the internal width of a section, the
 10 thickness of said legs being substantially equal to the internal thickness of a section, said pairs of members being disposed with the legs extending into adjacent sections and in edgewise contiguous relation to provide
 15 dividing lines along the longitudinal axes of said sections and means for locking pairs of oppositely disposed legs within their enclosing section.

8. A device of the class described comprising
 15 a plurality of flat tubular sections having a given internal width and thickness, pairs of flat U-shaped members, the legs of said members being of a width equally to substantially one half the internal width of a section, the thickness of said legs being substantially equal to the internal thickness of a section, said pairs of members being disposed with the legs extending into adjacent sections and in edgewise contiguous relation to provide
 25 dividing lines along the longitudinal axes of said sections and means for locking pairs of oppositely disposed legs within their enclosing section, said locked legs having a combined width substantially equal to the internal width of a section whereby the said legs are held in inter-locking relation.

9. In a band, chain or linkage, the combination of adjacent link-elements having hollow portions, and means for connecting a plurality of said link-elements in articulated relation comprising bifurcated members adapted for insertion into the hollow portions of two adjoining links to straddle the adjacent walls thereof, said connecting-members having complementary interlocking portions which secure them in position within the connected links.

10. An improved construction of band, chain or linkage for use in jewelry manufacture and kindred arts comprising a series of hollow link-elements arranged in adjacent relation, and pairs of complementary connecting members of bifurcated form having opposite legs adapted to be inserted into the hollow links in straddled relation with their adjoining side walls and formed with inter-engaging zig-zag portions adapted to interlock to permanently secure the parts of the device in assembled relation.

11. An improved construction of band, chain or linkage for use in jewelry manufacture and kindred arts comprising a series of tubular link-elements arranged with their side walls in adjacent relation, and means for coupling said link-elements in articulated relation comprising pairs of bifurcated connecting-members having parallel legs adapted to straddle the adjoining side walls of two adjacent link-elements and provided with notches in their opposite edges whereby said

members may be slid into the link-elements and the legs of one member sprung apart to pass over and interlock with the legs of the opposite member in the manner and for the purpose substantially as described.

12. A jointed band in which is comprised a series of sections of tubing arranged side by side in a row, and means flexibly joining the tubing sections comprising interlocking U-shaped elements each straddling opposite ends of two adjacent tubing sections and spring connected between the ends thereof.

13. A jointed band in which is comprised a series of tubing sections arranged side by side in a row having connecting means consisting in each instance of two U-shaped units with hooks at the free ends thereof adapted when entered into the tubing sections from opposite ends to effect a snap interengagement.

In testimony whereof I affix my signature.
 CHARLES DUERR.
